(57) **CLAIM**

The ornamental design for a drawer pull, as shown and described.

DESCRIPTION

FIG. 1 is a perspective view of a first embodiment of a drawer pull showing my new design in a closed position.

FIG. 2 is a front elevational view thereof.

FIG. 3 is a cross-sectional view along line 3—3 of FIG. 2.

FIG. 4 is a right side elevational view thereof.

FIG. 5 is a rear elevational view thereof.

FIG. 6 is a left side elevational view thereof.

FIG. 7 is a top plan view thereof.

FIG. 8 is a bottom plan view thereof.

FIG. 9 is a perspective view of the first embodiment of a drawer pull showing my new design in an open position.

FIG. 10 is a front elevational view thereof.

FIG. 11 is a cross-sectional view along line 11—11 of FIG. 10.

FIG. 12 is a right side elevational view thereof.

FIG. 13 is a rear elevational view thereof.

FIG. 14 is a left side elevational view thereof.

FIG. 15 is a top plan view thereof.

FIG. 16 is a bottom plan view thereof.

FIG. 17 is a perspective view of a second embodiment of a drawer pull showing my new design of indeterminate length in a closed position.

FIG. 18 is another perspective view thereof.

FIG. 19 is a front elevational view thereof.

FIG. 20 is a cross-sectional view along line 20—20 of FIG. 19.

FIG. 21 is a right side elevational view thereof.

FIG. 22 is a rear elevational view thereof.

FIG. 23 is a left side elevational view thereof.

FIG. 24 is a top plan view thereof.

FIG. 25 is a bottom plan view thereof.

FIG. 26 is a perspective view of a second embodiment of a drawer pull showing my new design of indeterminate length in an open position.

FIG. 27 is another perspective view thereof.

FIG. 28 is a front elevational view thereof.

FIG. 29 is a cross-sectional view along line 29—29 of FIG. 28.

FIG. 30 is a right side elevational view thereof.

FIG. 31 is a rear elevational view thereof.

FIG. 32 is a left side elevational view thereof.

FIG. 33 is a top plan view thereof.

FIG. 34 is a bottom plan view thereof.

FIG. 35 is a perspective view of a third embodiment of a drawer pull showing my new design in a closed position.

FIG. 36 is a front elevational view thereof.

FIG. 37 is a cross-sectional view along line 37—37 of FIG. 36.

FIG. 38 is a right side elevational view thereof.

FIG. 39 is a rear elevational view thereof.

FIG. 40 is a left side elevational view thereof.

FIG. 41 is a top plan view thereof.

FIG. 42 is a bottom plan view thereof.

FIG. 43 is a perspective view of the third embodiment of a drawer pull showing my new design in an open position.

FIG. 44 is a front elevational view thereof.

FIG. 45 is a cross-sectional view along line 45—45 of FIG. 44.

FIG. 46 is a right side elevational view thereof.

FIG. 47 is a rear elevational view thereof.

FIG. 48 is a left side elevational view thereof.

FIG. 49 is a top plan view thereof.

FIG. 50 is a bottom plan view thereof.

FIG. 51 is a perspective view of a fourth embodiment of a drawer pull showing my new design of indeterminate length in a closed position.

FIG. 52 is another perspective view thereof.

FIG. 53 is a front elevational view thereof.

FIG. 54 is a cross-sectional view along line 54—54 of FIG. 53.

FIG. 55 is a right side elevational view thereof.

FIG. 56 is a rear elevational view thereof.

FIG. 57 is a left side elevational view thereof.

FIG. 58 is a top plan view thereof.

FIG. 59 is a bottom plan view thereof.

FIG. 60 is a perspective view of a fourth embodiment of a drawer pull showing my new design of indeterminate length in an open position.

FIG. 61 is another perspective view thereof.

FIG. 62 is a front elevational view thereof.

FIG. 63 is a cross-sectional view along line 63—63 of FIG. 62.

FIG. 64 is a right side elevational view thereof.

FIG. 65 is a rear elevational view thereof.

FIG. 66 is a left side elevational view thereof.

FIG. 67 is a top plan view thereof; and,

FIG. 68 is a bottom plan view thereof.

The broken lines in FIGS. 1, 9, 17, 26, 35, 43, 51 and 60 are for illustrative purposes only and form no part of the claimed drawer pull.
